Specification of Letters Patent.

Patented Jan. 3, 1922.

Application filed October 29, 1918. Serial No. 260,111.

To all whom it may concern:

Be it known that I, ARTHUR H. ADAMS, a citizen of the United States, residing at Sparkill, in the county of Rockland, State 5 of New York, have invented certain new and useful Improvements in Printing Telegraphs, of which the following is a full, clear, concise, and exact description.

This invention relates to printing tele- 10 graphs and particularly to improvements in printing apparatus employed at receiving stations.

Some of the principal objects of this invention are to provide manually operable 15 means for effecting return of the type carriage; carriage return mechanism combined with line feed and ribbon feed mechanism; etc.

To the above ends means are provided for 20 distributing a series of current impulses to a plurality of selecting and operation-controlling magnets, which magnets control the selection of the desired character to be printed and operation to be performed. The in- 25 vention is disclosed in the accompanying drawings as applied to a telegraph receiving printer comprising stationary selecting mechanism, a stationary paper platen and printing elements adapted to be moved 30 transversely of the printer. The printing mechanism disclosed is of standard type- writer construction and is applicable to any suitable type bar typewriting machine.

Various auxiliary functions, such, for ex- 35 ample, as line feed and ribbon feed, carriage return, line feed and ribbon feed, character and word spacing, shift and unshift, etc., are controlled by a plurality of special code bars selectively controlled by line current 40 impulses. The various auxiliary operations of the printer are performed by a batter of rotating cams cooperating with suitable bell crank levers or operative members to effect the desired operation. The cam members 45 are mounted on a rotatable shaft to which power may be applied by means of a motor or any suitable driving mechanism.

The selecting mechanism disclosed consists of a plurality of stationary selecting 50 magnets and a corresponding number of horizontal selecting bars controlled by said magnets. The selecting bars extend entirely across the printer and are adapted to be raised and lowered but are not capable of 55 endwise movement.

A plurality of notched code bars or permutation bars are provided and the arrangement of these bars, with respect to the selecting bars, is such that when any combination is set up by the selecting magnets, only one 60 of the code bars will be permitted to move forward and mesh with the selecting bars. Each of the code bars which controls the printing of characters, cooperates with a pull bar which is adapted to be moved for- 65 ward by the code bar when selected into the path of a reciprocating printing bar which printing bar is controlled by the rotating cam shaft. When a pull bar is moved forward and engaged by the printing bar, a 70 type face carried by the corresponding type lever is thrust against the paper platen and the selected character printed.

The above and other objects of this invention will be fully set forth in the follow- 75 ing description and claims and will be more readily understood by reference to the accompanying drawings, in which Fig. 1 is a perspective view of the printing and selecting mechanism as assembled with certain 80 parts broken away to simplify the drawing and to more clearly show the cooperation between the various stationary and movable parts; Fig. 2 is a vertical sectional view of the mechanism disclosed in Fig. 1, together 85 with paper feeding and paper guiding mechanism, etc., Fig. 3 is a front elevation of the paper platen, paper guiding mechanism and paper holder disclosed in Fig. 2; Fig. 4 is a detail view of the automatic paper 90 travel correcting mechanism; Fig. 5 is a view showing a flexible metallic spring for causing the printing medium to conform to the periphery of the platen; and Fig. 6 is a view of an adjustable paper tearing edge. 95

The mechanism herein disclosed is operated preferably by a five-unit code with an additional impulse following each group of selecting impulses for starting the mechanism in operation. The selecting impulses 100 may consist of current of different polarity, different strength or the impulses may be formed by simply opening and closing the line circuit as in Morse operation. The impulses may arrive over a line from a distant 105 station and may be distributed to the selecting and starting magnets by means of a Baudot distributor or any of the well-known distributor systems.

In order to simplify the drawings, the 110

driving mechanism and a considerable portion of the frame structure have been omitted. Also various springs which would normally be used for restoring various operation parts to normal have been omitted to avoid complicating the drawings. It is to be understood, however, that suitable supporting means may be provided for the selecting and printing mechanism and that 10 springs may be provided, wherever necessary, to assist in the operation of parts or in restoring the various parts to normal.

This invention is an improvement upon the system disclosed in patent to Harry 15 Pfannenstiehl, No. 1,374,606, granted April 12, 1921, and since the above-mentioned co-pending application described in detail the various operations of a receiving printer, it is thought to be unnecessary to enter into a 20 detailed description of the mechanism herein disclosed, except in so far as such description is essential to a clear understanding of the new and novel features.

Referring to the drawings, and particularly to Fig. 1, the type carriage illustrated is of a form so well known as to require no detailed description. The type carriage 5 carries type bars, connecting links, code bars, etc., and is supported by a portion of 25 the frame 6 and rotatable shaft 7.

The selecting mechanism consists of five selecting magnets and five corresponding selecting bars 8, 9, 10, 11 and 12. Only two of the selecting magnets, 13 and 14, are shown. 30 The selecting bars 8 to 12 inclusive extend entirely across the printer at right angles to the character code bars 15 and the special code bars 16, 17, 18, 19, 20 and 21. Each of the selecting magnets is provided with an armature 22, 23, 24, 25 and 26, and extending from the armatures of the selecting magnets to the selecting bars are five latches, 27, 28, 29, 30 and 31. The latches normally extend beneath the selecting bars and are 35 adapted to be withdrawn when the selecting magnets are energized for selecting purposes. The selecting bars are normally held in the positions shown by means of the notched member 32, and when released and 40 permitted to drop they are held in their lower positions by means of springs 33 until restored by the upward movement of the member 32 in which position they are again held by the member 32 until a new selection 45 is set up. The selecting mechanism herein disclosed is the same as that disclosed in a co-pending application of Harry Pfannenstiehl and Erwin P. Bancroft, Serial No. 195,712, filed October 10, 1917, and therefore 50 further detailed description of the selecting mechanism is unnecessary.

As hereinbefore mentioned, the code bars are arranged so that when a selection is received, one and only one, of the code bars 55 will be permitted to move forward astride

the selecting bars. The code bars 15 are normally held in the position shown by means of a universal bar 34, which extends entirely across the type carriage in front of the extensions 35 carried by the bars 15. 70 The universal bar 34 and printer bar 38 are moved out of their normal positions by means of a striker bar 39, which is forced downwardly by the action of cams 40, 40, on cam shaft 41. The striker bar 39 is carried by two bracket arms 42 and 43 which are pivotally secured to a supporting rod 44. The rod 44 may be journaled in the sides of the printer frame or may be supported in any suitable manner. The bar 39 is normally held in the position shown by spring members 45, one end of which spring is connected to an extension of the bracket arms 42 and 43, while the other end of the spring is connected to an arm 115 of the eccentric 80 of cam 40. On each of the bracket arms 42 and 43 is secured an adjustable member 46, one of which is clearly shown in Fig. 2. On the supporting rod 44 and adjacent each of the bracket arms 42 and 43 is pivotally mounted an arm 47, which arms are oscillated by the cam 40. Each of the arms 47 carries a member 48, which is normally held in engagement with its corresponding adjustable member 46 by a spring 49, and may 90 be held away from the members 46 for certain purposes as will presently appear. It will be seen by reference, particularly to Figs. 1 and 2, that when the cam 40 moves the arm 115 forward the striker bar 39 will 100 be forced downward and by acting on the extensions 50 and 51 of crank lever 52 and arm 53, the universal bar 34 will be moved forward and the printing bar 38 will be moved upward. All of the code bars are 105 normally held clear of the selecting bars by the universal bar 34, and when the universal bar is moved forward all of the code bars, due to the action of suitable springs will also move forward slightly, but only the selected 110 code bar will be permitted to move forward astride the selecting bars. As the selected code bar moves forward, the extension 54 thereof moves a corresponding pull bar 4 into the path of the reciprocating printing 115 bar 38, so that on its downward stroke the printing bar strikes the end of the selected pull bar, thereby thrusting the desired type against the paper platen in a well-known manner.

Movement of the type carriage from left to right across the printer for character and word spacing is effected by the cam shaft and the type carriage is moved forward one step or one character space immediately 125 after each character is printed. A pivotally mounted rod 55 is provided which may be journaled in the frame of the printer or supported in any suitable manner. Rigidly secured to the rod 55 are two bracket arms 56 130

(only one of which is clearly shown) which carry the rack 57. Coöperating with the rack 57 and keyed to the rotatable shaft 7 is a worm wheel 58. On one end of the shaft 7 is a ratchet wheel 59, which is adapted to be rotated by an operating pawl 60. The pawl 60 is controlled by operating levers 61 and 62 and cam surface 63. The rotation of the ratchet 59 effects rotation of the shaft 7, and by means of the worm wheel 58 mounted thereon, the type carriage 5 is moved to the right one step or one character space for each group of character impulses, or whenever a spacing combination is transmitted.

It is necessary that means be provided to prevent spacing of the type carriage when certain auxiliary functions, such as line spacing, carriage shift, etc., are being performed. This is taken care of by providing some of the auxiliary code bars with an upwardly extending arm which is adapted to engage a bail 64 and move an upwardly extending arm 3 into the path of a reciprocating arm 65 carried by the rotatable shaft 7. Whenever the arm 65 is held against rotation the cam surface 66 carried thereby prevents the operating pawl 60 from engaging the teeth of the ratchet wheel 59, so that movement of the type carriage is prevented.

At the left-hand side of Fig. 1 is shown a plurality of special code bars 16 to 21 inclusive which are similar to the code bars 15 mounted on the movable type carriage 5. The special code bars are for the purpose of controlling the various mechanical operations such, for example, as line feed and ribbon feed, carriage return, line feed and ribbon feed, shift and unshift, etc. Code bars 16 to 21 inclusive are adapted to slide in recesses provided in the stationary supports 67 and are selectively controlled by line current impulses in the same manner as the character code bars, 15; that is, the various mechanical functions are selectively controlled by code signals which are transmitted in the same manner, and by the same means as the various character signals, also the power for performing the various mechanical functions, except line feed and ribbon feed, is supplied by the rotary cam shaft.

By reason of the fact that the paper platen is stationary and the type carriage movable, there is provided no common printing point. Consequently, it is not necessary to feed the inking ribbon as often or as frequently as if all characters were printed at a common point. Therefore applicant has provided means whereby the ribbon mechanism may be operated at the end of each line or whenever the platen is rotated to feed the printing medium forward for line spacing. For this purpose a special magnet 68 is provided for operating the line feed and ribbon feed mechanisms jointly. The magnet 68 is controlled by a special code bar 20. The code bar when selected is moved forward and engages connecting link 69, which is likewise moved forward. The rear end of the connecting link 69 is connected to a rocker arm 70 which is pivoted at 71. The opposite end of the rocker arm 70 is normally held against a member 72 by means of spring member 73, which tends to hold the rocker arm 70 in the position shown. Spring contacts 74 which control the circuit of the magnet 68 are normally open but are adapted to be closed by the rocker arm 70 when the special code bar 20 is selected. When the arm 70 is rocked to close contacts 74, member 72 is forced upwards and engages the off-set portion 75 of the arm 70 and holds the arm 70 in its actuated position, thereby retaining contacts 74 closed until the magnet 68 has completed its operation.

Magnet 68 is provided with a plunger or core 76 which controls the movements of arms 77 and 78. The arm 78 is pivoted at 79 and the arm 77 carried by arm 80 is likewise pivoted at 79. Arms 77 and 78 are operated simultaneously, the former controlling the operation of the ribbon feeding mechanism and the latter controlling the operation of the line feeding mechanism. The ribbon mechanism is shown in Fig. 2 comprising a ribbon spool 81 supported by a rotatable shaft 82 which is supported in any suitable manner. On the end of the shaft 82 is a pinion or bevel gear 83. Mounted at right angles to the shaft 82 is a rotatable shaft 84 which also carries a bevel gear adapted to mesh with gear 83. Rigidly secured to the shaft 84 is a ratchet 85. Loosely mounted on the shaft 84 is an arm 86 carrying a pin 87 and a pawl 88 which is adapted to engage the teeth of the ratchet wheel 85. The arm 77 when actuated engages the pin 87 carried by arm 86 and thereby effects rotation of the ratchet 85 by means of the pawl 88. Rotation of the ratchet 85 imparts rotation to the ribbon spool 81 and thereby advances the ribbon a predetermined amount. The ratchet 85 is also provided with a holding pawl 89 to prevent any backward movement of the ratchet.

The paper platen is provided with a ratchet wheel 90 which is adapted to be rotated for the purpose of rotating the paper platen and feeding the paper forward. Supported in the frame of the machine in any suitable manner is a slidable bar 91 carrying an actuating pawl 92. The pawl 92 is adapted to engage the teeth of the ratchet wheel 90 and advance the platen a predetermined amount. A lever 93 carrying a pin 94 is provided for determining the extent of rotation of the platen for each

actuation of the magnet 68. By movement of the lever 93 and pin 94, the holding pawl may be caused to rotate the platen the extent of one, or more teeth. The 5 slideable member 91 is provided with an extension 95 on the end therefor; which extension is engaged by the end of arm 78 whenever the said arm is rotated in a clockwise direction about its pivotal point 79. Thus it will be 10 seen that whenever magnet 68 is energized the paper platen and the ribbon spool will be rotated simultaneously, thereby controlling the spacing between lines and the advancing of the inking ribbon in one operation. 15

Type carriage return, line feed and ribbon feed.

The combined operation of ribbon feed 20 and line feed has just been described. When it is desired to commence a new line, it is invariably desirable to return the type carriage to the left-hand margin of the printing medium. By means hereinafter 25 described the operations of line feed, ribbon feed and carriage return, may be effected simultaneously and by one group of signaling impulses. These operations may be accomplished by sending over the line a 30 group of impulses to cause the selection of the special code bar 21, and release of the cam shaft 41. When the cam shaft is released and starts rotating, a cam 96 acting upon bell crank lever 97, will force the auxiliary striker bar 98 (which bar corresponds to the main striker bar 39) down against the action of suitable springs (not shown). The bar 98 acting upon bell crank levers 35 99 and 100 moves the auxiliary universal bar 101 (which bar corresponds to the main universal bar 34) forward and permits the selected special code bar 21 to move forward astride the selecting bars 8 to 12 inclusive. As the bar 21 moves forward under 40 the action of suitable springs, it performs two functions; first, it moves a pull bar 102 forward into the path of a reciprocating member 103 carried by the bell crank lever 104, which is operated by a cam 105 on the cam shaft 41; and secondly, by means of a pin 106 carried thereby, the connecting link 69 is engaged and moved forward to operate the rocker arm 70 and close the circuit contacts 74 which establish an 45 energizing circuit for the line feed and ribbon feed magnet 68. The pull bar 102 is connected to the rack 57 and when the rack is pulled down by the action of the pull bar the rack is disconnected from the worm 50 wheel 58 and is temporarily locked down by the locking disc member 107 carried by the shaft 7. The member 107 is normally held against the rack 57 by a spring 108 as shown in Fig. 1, and when the rack is depressed 55 60 the locking member 107 under the action of

the spring 108 engages the off-set portion 109 and holds the rack in its depressed position until the type carriage is completely returned by the action of a suitable spring and tape 110 whereupon the member 111 70 carried by the type carriage engages the disc 107 forcing it back against the action of spring 108, thereby permitting rack 57 to return to normal and reengage the worm wheel 58. Thus it will be seen that by 75 means of one group of signaling impulses the three auxiliary functions, namely, carriage return, line feed and ribbon feed may be effected simultaneously. It is preferable that when the type carriage is being re- 80 turned for commencing a new line there should be no unnecessary friction between the stationary and movable parts. Therefore it is desirable that means be provided to prevent the striker bar 39 from engaging 85 the arms 50 and 51 of the type carriage while it is being returned. This is accomplished by providing two arms 112 and 113 rigidly secured to the rod 55, so that when the rack 57 is depressed and the rod 55 rotated, arms 112 and 113 will act upon the members 48 and hold them out of engagement with the members 46, thereby preventing 90 actuation of the striker bar until the type carriage is returned and the rack 57 95 has been released. The striker bar 39 is normally held by means of spring 45 so that the adjustable member 46 presses against the end of the arm 48. The spring 45 is sufficient to hold the members 46 and 48 100 normally in engagement with one another and is of such strength that when the arm 48 is forced out of engagement with the member 46 and the reciprocating arm 115 moves forward, the spring 45 will prevent 105 the striker bar 39 from engaging the extensions 50 and 51.

Occasions frequently arise when the receiving operator desires to move or return the type carriage independently of the automatic means herein described. For the accomplishment of this object the supporting rod 55 is provided with a sleeve 116 which is rigidly secured thereto. The sleeve 116 carries a pin 117 which is adapted to be engaged by a manually operable lever 118 pivotally mounted on rod 55. When the lever 118 is pulled forward it engages the pin 117 and rotates the supporting rod 55. From reference to Fig. 1 it will be seen that the 115 bracket arms 55 and 56 (one of which is clearly shown) which support the rack bar 57, are rigidly secured to the shaft 55 so that when the shaft 55 is rotated the rack bar 57 will be moved out of engagement with the 120 worm wheel 58, and thereby permit the operator to move the type carriage freely to any desired position. When the rack bar 57 is moved out of engagement with the 125 worm wheel 58 the locking disk member 107 130

will engage the off-set portion at the rack 57 and hold it out of engagement with the worm wheel until the disk 107 is moved to its normal position to permit the rack bar to 5 return to normal.

Paper tearing edge.

In Figs. 1, 2 and 6 is shown an adjustable paper tearing edge which in addition to serving as a reliable and efficient paper tearing device in no way interferes with the visibility of the printed message. The paper tearing edge consists of a flexible cord or wire 119 stretched tightly across and near the paper platen. In Fig. 6 the cord 119 is shown connected at one end to a stationary member 120 on an upright 121, while the opposite end of the cord 119 is shown connected to an adjustable member 122 carried by an upright 123, which is rigidly connected to the corresponding upright 121 by the connecting portion 124. The holder consisting of the arms 121 and 123 and base portion 124 is arranged to be pivotally connected to any suitable part of the frame mechanism by means of hinges 125. In addition to the tearing edge 119 there is provided a similar cord or wire 126 which extends parallel with the cord 119 and is connected to the members 120 and 122 in the same manner as cord 119. The cord 126 is arranged to rest closely against the paper or printing medium while the tearing edge is held a slight distance away from the paper. The cord 126 serves to retain the paper in engagement with the platen when the strip or sheet is torn off along the cord 119, thereby making it unnecessary to start the end of the paper under the tearing edge by hand. It is desirable that the tearing edge be of small diameter and of material having high tensile strength. In this connection fine piano wire has been found to be very satisfactory.

The paper tearing edge is useful only when employing roll paper or paper of continuous length and is non-essential when the printer is used for manifolding or when employing sheets of uniform length. Therefore, when manifolding, the tearing edge 45 and holder therefor may be rotated about its pivotal bearings 125 and turned into the position shown in dotted lines (Fig. 2). Combined with the paper tearing edge is a set of presser rollers 127 and 128, which rollers are adapted to be held in close proximity with the paper platen when single strips of paper are employed. There is one presser roller provided near each end of the paper platen and each roller extends through an 50 opening in a paper shield 129 and is normally held in position by means of supporting members 130 which are held in position by spring members 131 as shown in full line (Fig. 2). These rollers aid in 55 guiding the paper around the periphery of

the platen and are useful only when feeding single strips of paper. Therefore it is desirable that the rollers be removed from the platen when manifolding or when feeding a plurality of sheets simultaneously. When 70 the paper tearing edge is thrown back into the dotted line position (Fig. 2), the portion 124 connecting arms 121 and 123, is moved into the dotted line position, thereby forcing the members 130 and the presser 75 rollers carried thereby down into the position shown in dotted lines. Thus it will be seen that the members 121, 123 and 124 not only serve as a support for the paper tearing edge but also serve to remove the presser 80 rollers from engagement with the paper platen when they are not required. Another advantageous feature of this arrangement is that when a new roll of paper is placed in the machine and it is desired to start the 85 paper around the periphery of the platen the paper tearing edge may be moved to a position intermediate of the two positions shown in Fig. 2, and in so doing the presser rollers will be lowered, thereby making it easy to 90 start the paper around the platen.

Automatic paper guiding device.

The paper or printing medium on which the received messages are recorded is commonly used in roll form which may be mounted on a dowel or spindle 132 as clearly shown in Fig. 3. The dowel 132 is provided with spring members 133 for holding the paper roll in position. The dowel 132 is 95 provided with a metal pin extending through the center thereof which pin is supported at each end by the frame of the machine. To prevent the roll from turning too freely there is provided a spring member 146 which 100 engages the end of the supporting pin, and forces the dowel 132 against the support 134. The friction set up between the spring 146 and metal pin and between the dowel 105 and support 134 is sufficient to prevent the roll from overrunning. The paper 135 is drawn from the under side of the roll over a spring supported idler or guiding roller 136, thence under, around and over the platen, thence over the paper supporting fingers 137 to a suitable spool or take-up device. The guide roller 136 consists of a cylindrical surface with spool heads at each end thereof and rigidly secured to a rod or center pin 138. The spool or roller 136 is 110 supported at each end by flexible springs 139 and 140, one end of each spring being rigidly connected to a suitable portion of the frame and the other end arranged to loosely engage the rod 138. So long as the 115 paper is fed straight forward step-by-step by means of the line spacing mechanism hereinbefore described, the roller 136 and spring supporting members will oscillate 120 freely up and down and gradually with- 125 130

draw the paper from the paper roller as desired. However, it frequently happens that the paper instead of being fed forward horizontally in a straight path will travel faster 5 along one edge than the other and will cause the characters to be printed in lines diagonally of the paper and may even eventually prevent or interrupt the feeding of the paper. To avoid such a condition this invention 10 contemplates the provision of means for automatically correcting the feeding of the paper. This feature is clearly demonstrated in Figs. 3 and 4. In case the paper, due to unevenness of thickness, different pressures 15 being applied to the presser rollers, or for any reason whatever, travels faster on one side than on the other and consequently travels over to the right or left of the center, the paper in passing over the guide 20 roller 136, will force the roller and supporting pin 138 sidewise, so that the end of the pin 138 will engage the stationary frame 141. Therefore, as soon as one end of the rod 138 is held rigid by its engagement with 25 the stationary part of the printer frame, only one end of the guide roller will be free to oscillate, and will therefore automatically correct the travel of the paper by causing a greater pull on the edge of the paper which 30 has been gradually falling behind, and as soon as the travel of the paper is corrected the guide roller will be moved to its former position so that it will again be free to oscillate until the paper forces it in one direction or the other a sufficient distance to 35 again cause the rod 138 to engage the stationary frame portion of the printer.

The paper guide fingers 137 are carried by flexible spiral springs 142 and 143, which 40 springs are mounted on arms 144 and 145 respectively, and which arms are pivotally connected in any suitable manner to the frame. It will be noted that the guide fingers are so supported that the center of the 45 paper is open or exposed thereby making it easy to change the paper rolls and to start new strips of paper around the platen. These fingers are also arranged so that when manifolding or when feeding a plurality 50 of sheets, the fingers may be moved back out of the way as shown in the dotted line position (Fig. 2). This position is of positive utility in handling books of flimsy, keeping them out of the cam shaft.

55 Fig. 5 is a detail view showing a paper shield or guide 129 and a flexible metallic band 146 for causing the printing medium to conform to the periphery of the platen. One end of each metallic spring is connected 60 to a set of flexible fingers 147 best shown in Fig. 1, which fingers are also for the purpose of holding the paper close to the platen. The other end of each metallic band 146 is connected by a spring 148 to the paper shield

129 or any suitable stationary part of the 65 frame.

What is claimed is:

1. In a telegraph receiver in combination with a movable carriage, a selecting mechanism, code bars cooperating with said selecting mechanism, means for moving said carriage in one direction step by step, a paper platen, mechanism for rotating said platen for line spacing, ribbon feeding mechanism, and means controlled by one of said code bars for operating said line spacing and ribbon feeding mechanisms and for effecting return of the carriage. 70

2. In a telegraph receiver in combination with a movable carriage, a selecting mechanism comprising selecting magnets and selecting bars controlled thereby, means for moving said carriage in one direction step by step, a paper platen, mechanism for rotating said platen for line spacing, ribbon 85 feeding mechanism, and means controlled by one of said code bars for operating said line spacing and ribbon feeding mechanisms simultaneously and for effecting return of the carriage. 90

3. In a telegraph receiver in combination with a movable carriage, a selecting mechanism, code bars cooperating with said selecting mechanism, means for moving said carriage in one direction step by step, a 95 paper platen, mechanism for rotating said platen for line spacing, ribbon feeding mechanism, a magnet for operating said line spacing and ribbon feeding mechanisms, and a code bar for effecting return of the carriage and for controlling the operation of 100 said magnet.

4. In a telegraph receiver, the combination of a movable type basket comprising a plurality of type bars, a rack, a worm gear 105 cooperating with said rack for moving said type basket in one direction step by step for line printing, means normally tending to return said type basket, and a plurality of devices for effecting the disengagement of 110 said rack and worm gear to permit the return of said type basket.

5. In a telegraph receiver, the combination of a stationary platen, a type carriage comprising a plurality of type bars movable transversely with respect to said platen, a rack, a worm gear cooperating with said rack to move said carriage in one direction step by step for line printing, means normally tending to return said carriage, and 115 manually operable means associated with said rack for effecting the removal thereof from said worm gear to permit the return of 120 said carriage.

6. In a telegraph receiver, a movable type 125 carriage comprising a plurality of type bars, a rack, a worm gear cooperating with said rack for moving said carriage in one direc-

tion, step by step for line printing, means normally tending to return said carriage, selectively operable means for returning the carriage to normal, and means independent 5 of said selectively operable means for effecting return of the carriage.

7. In a telegraph receiving printer, the combination of a movable type carriage comprising a plurality of type bars, a rack, a 10 worm gear cooperating with said rack for moving said carriage in one direction step by step for line printing, means normally tending to return said carriage, mechanical means selectively operable for disengaging 15 said rack and worm gear to permit the return of said carriage to normal, and means independent of said mechanical means for effecting the return of said carriage.

8. In a telegraph receiving printer, the combination of a movable type carriage comprising a plurality of type bars, a rack, a 20 worm gear cooperating with said rack for moving said carriage in one direction step by step for line printing, means normally tending to return said carriage, mechanical 25 means selectively operable for disengaging said rack and worm gear to permit the return of said carriage to normal, and manually operable means independent of said mechanical means for effecting the return of 30 said carriage.

In witness whereof, I hereunto subscribe my name this 18th day of October, A. D. 1918.

ARTHUR H. ADAMS.
